UNITED STATES PATENT OFFICE

LE ROY B. ALLEN, OF NORWALK, OHIO.

DESIGN FOR A CHECKREIN-HOOK.

SPECIFICATION forming part of Design No. 35,151, dated October 1, 1901.

Application filed July 25, 1901. Serial No. 69,736. Term of patent 14 years.

To all whom it may concern:

Be it known that I, LE ROY B. ALLEN, a citizen of the United States, residing at Norwalk, in the county of Huron and State of Ohio, have invented and produced a new and original Design for a Checkrein-Hook; and I do hereby declare the following to be a full, clear, and exact description of the same, reference being had to the accompanying drawings, forming a part thereof.

This invention relates to a new and original design for a checkrein-hook.

As shown in the accompanying drawings, the design comprises a horizontal base portion A, having at one end a hook member B and at the opposite end a post or stem C. Extending upwardly from the base and inclosed within the hook B is a small stud or projection D. Extending downwardly from the

base are two shanks E and e, a portion of the same being roughened in the nature of a screw-thread. The ends of the base A are curved downwardly, as indicated at a a'.

The essential features of the design are the base portion having the curved ends a a', the stem C, and the stud D, inclosed within the hook B.

Having thus described the invention, what is claimed as new, and desired to be secured by Letters Patent, is—

The design for a checkrein-hook, substantially as shown and described.

In testimony whereof I affix my signature in presence of two witnesses.

LE ROY B. ALLEN.
